UNITED STATES PATENT OFFICE.

WILLIAM A. FAIRBURN, OF SHORT HILLS, NEW JERSEY, ASSIGNOR TO THE DIAMOND MATCH COMPANY, OF CHICAGO, ILLINOIS, A CORPORATION OF ILLINOIS.

SPLINT-IMPRFGNATING MEANS FOR MATCH-MACHINES.

1,255,999.

Specification of Letters Patent. Patented Feb. 12, 1918.

Application filed May 1, 1915. Serial No. 25,121.

To all whom it may concern:

Be it known that I, WILLIAM A. FAIRBURN, a citizen of the United States, and resident of Short Hills, in the county of Essex and State of New Jersey, have invented certain new and useful Improvements in Splint-Impregnating Means for Match-Machines, of which the following is a specification.

10 This invention relates to means for treating match splints with powdered material adapted to impart to the splints a non-glowing property.

The object of my invention is to provide a simple and efficient means whereby the powdered material is economically and uniformly applied to and throughout the length of the splints during the operation of converting them into matches on a continuous

20 match making machine.

To this end my invention, broadly considered, comprehends an apparatus having provisions whereby the powdered material is forcibly blown among and against the 25 splints on the progressing splint carrier in such a manner as to incorporate the material effectively with the surface of the wood and thereby impart to the splints the requisite non-glowing property.

30 The invention also comprises various features of construction and combinations of parts whereby beneficial results are attained, as will be hereinafter described and claimed.

In the drawings—

35 Figure 1 is an end elevation, partly in section, of an apparatus embodying the principle of my invention; the splint carrier of the match machine being shown in cross-section.

40 Fig. 2 is a partial longitudinal vertical section of the apparatus, as on the line 2—2 of Fig. 1; certain parts being broken away to show internal elements.

Fig. 3 is a horizontal section, as on the line 45 3—3 of Fig. 1.

Fig. 4 is a vertical section, as on the line 4—4 of Fig. 1.

Referring to the drawings, 10 designates a part of a splint carrier comprising in the 50 present illustration a series of perforated plates hinged or linked together to form an endless chain, into the perforations of which plates the match-splints are inserted row by row and thereby transported through the 55 match making path. Suitably-located be-

neath the route of the carrier after it leaves the splint inserting station is a structure into which project the depending splints during their travel across the structure. This structure in its preferred form comprises oppositely inclined side walls 11 and end walls 12 arranged to provide a relatively capacious chamber within which the splints are treated with an anti-glowing material, such, for example, as finely-divided ammonium phosphate. The upper edges of the side walls of the structure are furnished with ledges 13 upon which the longitudinal edges of the carrier are guided and supported; and the upper portions of the end walls are open, as 70 at 14, to permit the free passage of the splints into, through and from the chamber. The side walls are provided longitudinally thereof with exterior air chests 15 communicating with the interior of the casing structure 75 through numerous nozzles 16 which are so angularly disposed as to discharge the air from the respective chests in intersecting planes toward the horizontal path of the splints on the carrier. The chests are connected at one end of the structure by means of branch pipes 17 with the diverging delivery pipes 18 of a blower 19, or other appropriate air engine, whereby air under relative high pressure is uniformly delivered 80 to the respective chests 15 and thence injected into the impregnating chamber.

The delivery pipes 18 terminate in two horizontal extensions 20 which are disposed adjacent the respective sides of the casing 90 in substantially the same horizontal plane as the splints in the carrier. The extensions 20 are provided at intervals with nozzles 21 which open into ducts 22 leading from longitudinally disposed receptacles 23 into 95 the interior of the casing adjacent the horizontal path of the splints. Within each of the receptacles, which are in the form of cylindrical conduits, is a screw-conveyer 24 which is mounted and operated to feed 100 powdered impregnating material longitudinally of the conduit and into the respective ducts 22, such material being thence forcibly injected into the path of the splints by and with the blasts of compressed air 105 from the nozzles. The material thus injected impinges forcibly against the opposing splints and is in consequence well incorporated with the surface of the wood in a manner to secure uniform and effective "impreg- 110

nation" throughout the length of the splints. This result is contributed to by the action of the air blasts from the nozzle 16, in that the blasts intercept the powder 5 within the chamber in intersecting planes and distribute it thoroughly among the splints. The powder which settles to the bottom of the chamber is removed therefrom by a screw-conveyer 25 which is mounted to rotate in a channel 26 formed in the casing. The shaft of this conveyer has its bearings in the end walls of the casing, and that end of the shaft adjacent the fan bears a sprocket wheel 27 which is connected by means of a chain 28 with a similar wheel 29 on a shaft 30 which is appropriately geared with the power driven blower shaft 31, as, for example, by meshing bevel wheels 32, 33 respectively. Thus 10 the conveyer is continuously driven during the operation of the fan, and the conveyer 15 perforce progressively feeds the material to one end of the channel 26. Such end is provided with diverging chutes 34 which lead 20 respectively to suitably-disposed receptacles 35 and deliver the material thereto. Mounted on sprocket wheels 36 in these receptacles are endless chain conveyers 37 which extend above and are guided and supported by suitably-disposed wheels 38 located adjacent the respective conduits. These conveyers travel in casings 39 extending from the receptacles 35 and they (the conveyers) are appropriately arranged and 25 driven to carry the material from such receptacles and discharge it into the receiving end of each of the conduits 23 above referred to. In the present instance, the shaft of each of the wheels 36 is provided with 30 a sprocket wheel 40 which is connected by means of a chain 41 with and driven from a wheel 42 on the projecting end of the shaft of the screw conveyer 25 in the bottom of the impregnating chamber; and the shaft 35 of the screw conveyer 24 of each of the conduits 23 is conveniently geared with and driven by the shaft of the wheel 38 of the adjacent chain conveyer by means of a sprocket chain 43 passing about wheels 44, 45 on the latter two shafts respectively.

Arranged above the impregnating structure, in spaced relation to the upper surface of the splint carrier, is a cover or bonnet 46, from one end of which rises a tapering duct 47 merging with an exhaust pipe 48 by way of which the powder escaping through the holes and spaces of the carrier, is withdrawn. A rotary brush 49 mounted at the mouth of the duct 47 so as to sweep 50 the upper surface of the carrier, serves not only to prevent the escape of the powder to the open air, but also to clear the powder from the top of the carrier as it progresses from the impregnating structure.

65 Although any suitable means may be em-

ployed for primarily supplying the impregnating powder to the conduits, I prefer to use for this purpose devices of the following description:

50 designates a supply hopper into which the material is introduced; and 51 designates an air and powder separator which is connected with the lower funnel-shaped discharge end of the hopper by means of a conduit 52. This conduit is provided with 75 a feed device, such as a conveyer screw 53, the shaft of which has its bearing in the closed outer end of the conduit, whereby when the screw is properly rotated the contents of the funnel are progressively fed into 80 the interior of the separator 51. The lower end of the latter is funnel-shaped and it discharges into powder grinding mill 54 of any usual or approved construction, having diverging chutes 55 leading into the receiving ends of the respective conduits 23. The mill herein illustrated is provided with co-acting grinding rolls 56 the shafts of which bear intermeshing gear wheels 57. The outwardly projecting end of one (58) 90 of these shafts has fast thereon a sprocket wheel 59 which is geared by means of a chain 60 with a similar wheel 61 on the shaft of the upper sprocket wheel 38 of one of the chain conveyers 37. The shaft 95 58 is also provided with a sprocket wheel 62 which is connected by means of a chain 63 with a similar wheel 64 on the shaft of the feed screw 53. Thus the screw and the grinding rolls are driven concurrently, and 100 in consequence the material is progressively transferred from the hopper to the grinder, and is thereupon ground and delivered thence to the respective conduits 23.

The air supply pipe 65 leading to the 105 in-take of the blower 19 is connected with an outlet in the top of the separator, and the exhaust pipe 48 from the bonnet above the carrier is extended upward and connected with a tangential inlet in the side of the 110 separator.

The separator may be of any known or approved type which while establishing air communication between the pipes 48, 65, operates effectually to separate the powder from 115 the air and allow the powder thus separated to reenter the grinder. In the present instance a separator or "dust collector" of the Morse type is somewhat generally indicated, the same, briefly described, comprising a 120 casing of appropriate form having therein a central air chamber 66 and an annular powder chamber 67, such chambers being partitioned by edge spaced separating members 68. An air current being established 125 at the outlet of the separator by the action of the blower, the powder-laden air is thereby drawn from the bonnet and is caused to flow tangentially into the central chamber of the separator in a whirling current which 130

impinges against the inner faces of the separating members 68, the centrifugal action causing the powder to be projected against such members and to be skimmed through 5 the spaces therebetween into the chamber 67. Such powder accumulating within the latter chamber, falls to the bottom thereof and passes thence to the grinder; while the filtered air flows to the blower.

10 A characteristic feature of my invention as exemplified by the construction above described is that powdered impregnating material is forcibly blown against and among the splints in such a manner as to 15 effect and insure the incorporation of the powder with and throughout the surface of the splints, which result it is to be noted cannot be satisfactorily attained by simply floating the powder among the splints, as in 20 the latter case a mere superficial dusting of the splints is had which is irregular and uncertain in its application, is ineffective in its action, and is otherwise unreliable.

It is to be understood that the invention 25 is not limited to the precise construction herein shown and described, as the structural features may be modified without departure from the spirit of the invention.

What I claim is—

30 1. The combination with a carrier constructed to support depending match splints in spaced relation to each other, of a structure having a chamber arranged directly beneath and adjacent to the path of the under- 35 side of the carriage, said chamber having inlet and outlet portions for the passage of the carrier, whereby the splints on the carrier progress into and through said chamber, and pneumatic means for forcibly 40 projecting impregnating powder toward, against and among the depending splints within said chamber.

2. In splint-impregnating means for match 45 machines having a splint carrier, a structure having a chamber adapted to receive the splints during their travel, ducts opening into said chamber, means for supplying impregnating powder to said ducts, nozzles projecting into said ducts and toward said 50 chamber, and means for supplying air to said nozzles.

3. In splint-impregnating means for match 55 machines having a splint carrier, a structure having a chamber adapted to receive the splints during their travel, ducts opening into said chamber adjacent the horizontal path of the splints, means for supplying impregnating powder to said ducts, nozzles projecting into said ducts and toward 60 said chamber, and means for supplying air to said nozzles.

4. In splint impregnating means for match 65 machines having a splint carrier, a structure having a chamber adapted to receive the depending splints during their travel,

ducts opening into said chamber, means for supplying impregnating powder to said ducts, nozzles projecting into said ducts and toward said chamber, lower nozzles projecting upwardly within said chamber toward the path of the splints, and means for supplying air to the upper and lower nozzles.

5. In splint impregnating means for match 70 machines having a splint carrier, a structure having a chamber adapted to receive the splints during their travel, a conduit having ducts at intervals communicating with the said chamber, means for supplying impregnating powder to said conduit, and 75 pneumatic means for forcing air through said ducts and into the chamber.

6. In splint impregnating means for match 80 machines having a splint carrier, a structure having a chamber adapted to receive the splints during their travel, conduits adjacent the sides of the structure having ducts at intervals communicating with the said chamber, means for feeding impregnating powder along said conduits, and 85 pneumatic means for forcing air through said ducts and into the chamber.

7. The combination with a carrier constructed to support depending match splints in spaced relation to each other, of a structure 90 having a chamber arranged directly beneath and adjacent to the path of the underside of the carrier, said chamber having inlet and outlet portions for the passage of the carrier, whereby the splints on the carrier 95 progress into and through said chamber, pneumatic means for forcibly projecting impregnating powder toward, against and among the depending splints within said chamber, and means for removing accumulating 100 material from the bottom of said chamber.

8. The combination with a carrier constructed to support depending match splints in spaced relation to each other, of a structure 110 having a chamber arranged directly beneath and adjacent to the path of the underside of the carrier, said chamber having inlet and outlet portions for the passage of the carrier, whereby the splints on the carrier 115 progress into and through said chamber, a receptacle for impregnating powder, said receptacle communicating with the chamber, pneumatic means for forcing the powder from said receptacle into said chamber, 120 means for removing accumulating powder from the bottom of said chamber, and means for returning such accumulating powder to said receptacle.

9. In splint impregnating means for 125 match machines having a splint carrier, a structure having a chamber adapted to receive the splints during their travel, conduits adjacent the sides of the structure having ducts at intervals communicating with the 130

4
said chamber, means for feeding impregnating powder along said conduit, pneumatic means for forcing air through said ducts and into the chamber, means for removing accumulating powder from the bottom of said chamber, and means for returning such accumulating powder to the said conduits.

10. The combination with a carrier constructed to support depending match splints in spaced relation to each other, of a structure having a chamber arranged directly beneath and adjacent to the path of the underside of the carrier, said chamber having inlet and outlet portions for the passage of the carrier, whereby the splints on the carrier progress into and through said chamber, pneumatic means for forcibly projecting impregnating powder toward, against and among the depending splints within said chamber, and means above the structure for receiving and carrying off the powder escaping above the carrier.

11. The combination with a carrier constructed to support depending match splints in spaced relation to each other, of a structure having a chamber arranged directly beneath and adjacent to the path of the underside of the carrier, said chamber having inlet and outlet portions for the passage of the carrier, whereby the splints on the carrier progress into and through said chamber, pneumatic means for forcibly projecting impregnating powder toward, against and among the depending splints within said chamber, a cover for the carrier directly above the chamber, and operative connection between the interior of said cover and said pneumatic means.

12. The combination with a carrier con-

structed to support depending match splints 40 in spaced relation to each other, of a structure having a chamber arranged directly beneath and adjacent to the path of the underside of the carrier, said chamber having inlet and outlet portions for the passage of the 45 carrier, whereby the splints on the carrier progress into and through said chamber, pneumatic means for forcibly projecting impregnating powder toward, against and among the depending splints within said 50 chamber, a cover for the carrier directly above the chamber, a separator communicating with the said receptacle, a connection between said cover and the separator, and a connection between said separator and the 55 pneumatic means.

13. The combination with a carrier constructed to support depending match splints in spaced relation to each other, of a structure having a chamber arranged directly beneath and adjacent to the path of the underside of the carrier, said chamber having in its upper portion inlet and outlet portions for the passage of the carrier, whereby the splints on the carrier progress into and 60 through said chamber, an air engine, means connected therewith whereby impregnating powder is forcibly blown into the upper portion of the chamber and across the path of the splints in their traverse through said 65 chamber, and means connected with said engine whereby upward air blasts directed to the splints are established within the chamber.

Signed at New York, in the county and 75 State of New York, this 30th day of April, A. D. 1915.

WILLIAM A. FAIRBURN.
